Arthur W. Harrison.

UNITED STATES PATENT OFFICE.

BENJAMIN DAVIES, OF BROOKLYN, ASSIGNOR TO L. STRAUS & SONS, OF NEW YORK, N. Y.

DESIGN FOR THE ORNAMENTATION OF GLASS VESSELS.

SPECIFICATION forming part of Design No. 22,286, dated March 14, 1893.

Application filed February 1, 1893. Serial No. 460,614. Term of patent 7 years.

To all whom it may concern:

Be it known that I, BENJAMIN DAVIES, of Brooklyn, in the county of Kings and State of New York, have invented and produced a new and original Design for the Ornamentation of Glass Vessels; and I do hereby declare the following to be a full, clear, and exact description of the said invention, reference being had to the accompanying drawings, and to the letters of reference marked thereon, which form a part of this specification.

In the drawings, Figure 1— is a plan view of a vessel ornamented with my design, and Fig. 2— represents a cross sectional view of the same.

The leading features of my design consist of a series of groups of four radiating grooves, the grooves of the series crossing each other, the central inner spaces of each group having a small spray of grooves and the outer central spaces having a larger spray or fan of grooves, the two inverted kite-shaped spaces having fine cross grooved fields and the four triangular shaped spaces having fine parallel grooves.

In the center of the design is a star A of ordinary pattern to which I make no claim. From different points outside of this star, deep grooves B, radiate, the outer ends of the

grooves of each group meeting the outer ends 30 of the outer grooves of the third group therefrom, as indicated at b, and also meeting at the same point (b), the outer ends of the intermediate grooves of the second group. The inner points of radiation are indicated at b'. 35 In the central inner space or each group is a spray of grooves C, while the outer central spaces are occupied with larger sprays of grooves of fan-figures D. The larger spaces between the grooves B, having somewhat the 40 shape of inverted kites, are occupied by fields E, of fine crossed grooves and the small triangular spaces F, between said grooves B, are each occupied by small grooves parallel with each other and with the short side of the triangle. 45

Having thus described my invention, what I claim is—

The design for the ornamentation of glass vessels, substantially as herein shown and described. 50

In testimony whereof I affix my signature in presence of two subscribing witnesses.

BENJAMIN DAVIES.
